The single figure is a front perspective view of shorts showing my new design, the back being conventional and plain.

The characteristic feature of my design resides in a combination on the shorts disclosed of a wide and a narrow diagonal stripe on each side extending from the lower portion of the pocket area to the belt area, substantially as shown.

This is a division of my copending application D. 13,566 filed Sept. 17, 1968.

I claim:

The ornamental design for shorts, as shown and described.
